[57] CLAIM

The ornamental design for a table, as shown and described.

DESCRIPTION

FIG. 1 is a perspective view of our new design for a table; FIG. 2 is a left side view thereof, wherein the right side view of the table of FIG. 1 is identical to the left side view of FIG. 2;

FIG. 3 is a front view thereof, wherein the rear view of the table of FIG. 1 is identical to the front view of FIG. 3; FIG. 4 is a top view thereof; and,

FIG. 5 is a bottom view thereof.
